ARTHUR ORLOFF, OF GREEN BAY, WISCONSIN, ASSIGNOR TO NORTHWEST ENGINEERING CORPORATION, OF GREEN BAY, WISCONSIN, A CORPORATION OF WISCONSIN

BACK DIGGER

Application filed April 22, 1929. Serial No. 357,067.

The invention relates to excavators and more particularly those of the type usually called pull shovels, trench hoes or back diggers.

5 The usual type of pull shovel, wherein the hoist cable extends out to the outer end of the boom and over sheaves at the end of the boom, or associated with the dipper handle so that said hoisting line and its sheaves get 10 into the trench during digging, present a fruitful source of trouble inasmuch as it is impossible to keep dirt and grit from falling into the sheaves, with resultant troubles due to rapid wearing of the moving parts, particularly the cable, as when small stones get 15 between the cable and sheaves, cutting and consequent breakage are apt to result. According to the present invention these disadvantages are overcome by providing a hoisting cable separate from the dipper stick to raise and lower the boom and to utilize the compression forces transmitted through the boom due to the weight of the boom, dipper and dipper handle to effect the operation of 20 other means which move the dipper and its stick angularly relative to the boom.

A further object of the invention is to provide a novel arrangement for swinging the dipper and its handle relative to the boom 30 wherein the desired effect is obtained of having less outward swinging force upon the dipper handle occur when the boom is lowered into the trench than when it is elevated in the dumping position. This is obtained 35 in the present arrangement because in the upper position the weight of the dipper and its handle tends to move the dipper inward while in the extreme lower position this weight tends to swing the dipper outward. 40 Consequently, in the lower positions less additional force is required to swing the dipper outwardly to a certain angle with respect to the boom.

A further object of the invention is to 45 provide a swinging support for the the piv-

otal mounting of the boom which support is connected by cable with the dipper handle to effect an angular outward movement of the dipper and dipper handle relative to the boom in different positions thereof and under 50 the control of another cable which also effects an inward swinging movement of the dipper and its handle relative to the boom.

The invention further consists in the several features hereinafter set forth and more 55 particularly defined by claims at the conclusion hereof.

The drawing shows an elevation view of an excavator embodying the invention.

Referring to the drawings the numeral 4 60 designates the traveling base of the machine equipped with endless propelling treads 5 driven in known manner from a suitable prime mover 7 on the rotating base 6 of the machine, 8 a swinging boom pivot support or 65 lever pivotally connected at one end by a pin 9 to the base 6 and having the boom 10 pivotally connected to said lever at an intermediate point by a pin 11 whereby said boom is mounted for up and down movements relative to the machine base and also for angular movements relative to said support 8. 70

A dipper handle or stick 12 is pivotally connected intermediate its ends by a pin 13 to the outer end of the boom and carries a dipper 14 facing toward the machine and equipped with digging teeth 15. 75

The usual drag cable 16 passes from the drag drum 17 over a pulley or sheave 18 on the boom 10 to a point of pivotal connection 80 at 19 with the dipper, the winding in of the drag cable swinging the dipper and its handle inwardly toward the machine to effect a digging movement when the boom is lowered and in operative position relative to the trench and to effect the retention of the load in the dipper when the boom is in an elevated position, or to retain the dipper in any desired angular position against forces tending to move it 85 outwardly relative to the boom. 90

For raising and lowering the boom, dipper and dipper handle, a hoisting cable 20 passes from the hoist drum 21 over a guide sheave 22 on the shear leg 23, thence around a sheave 24 mounted on the medial portion of the boom or back from its forward end and is dead ended on the machine, as by a connection with said shear leg. Thus winding in on the hoisting cable raises the boom 10 and the parts carried thereby and paying out of this cable lowers these parts.

The drums 17 and 21 are equipped as usual with brakes and clutches to control their operation.

15 The free end 25 of the boom support or lever 8 has a link or pull connection with the upper end of the dipper handle. This connection preferably comprises a cable 26 whose ends are suitably pivotally connected respectively with said end 25 and with said handle, as at 27.

With this construction when the boom is in a raised position a portion of its weight and that of the dipper and dipper handle will 25 react against the rocking or pivotal lever or support 8 through which it is connected to the base of the machine and will tend to swing the free end of said lever 8 inwardly and through this reaction exert a pull on the 30 cable 26 toward the machine, which is of a length to thereby produce a pull on the dipper handle which acts to swing the dipper handle and dipper outward relative to the boom, as shown in full lines in the drawing. When, 35 however, the dipper is lowered into the trench, the weight of the boom tends to pull the lever 8 outward, with the result that there is less tendency to swing the dipper outward, as shown by the dotted line position of the parts, 40 and under these conditions a hauling in of the drag line 16 causes the inward swinging or digging movement of the dipper and a retention of the dipper in its inward position relative to the boom after digging permits the 45 hoisting cable to be operated to raise the boom and dipper to an elevated position and the swinging of the boom to a position of discharge, at which time a paying out of the drag line permits the lever 8 and cable 26 to effect 50 the outward movement of the dipper handle and dipper to discharge its load or, if desired, the dipper may be provided with a bottom dumping door, long well known in excavators, for discharging its load, or other 55 forms of discharge means for the dipper may be used.

From the foregoing description it will be noted that I have provided a pull shovel construction in which the component of weight of the parts exerted along the boom is used to effect movement of means operatively connected to the dipper handle to effect shifting movements of the dipper and dipper stick and 65 that such component has a greater effect when

the boom is in a raised position than when it is in a lowered, digging position.

I desire it to be understood that this invention is not to be limited to any particular form or arrangement of parts except insofar as such limitations are included in the claims or necessitated by the prior art.

What I claim as my invention is:

1. In an excavating machine, the combination of a base, a movable boom support 75 mounted on said base, a boom pivotally mounted on said support for up and down movements and so that its pivot moves relative to the base of the machine during the digging cycle, a dipper handle pivotally mounted on the outer end portion of said boom and carrying a dipper working toward the machine during digging, a hoisting cable associated with the boom, and means associated with said support and moved thereby 80 under the forces exerted thereon by the boom for effecting shifting movements of the dipper and dipper handle relative to the boom.

2. In an excavating machine, the combination of a support pivotally mounted on the 90 machine, a boom pivotally mounted on said support for up and down movements and for moving said support during the digging cycle, a dipper handle pivotally mounted on the outer end portion of said boom and carrying a dipper working toward the machine during digging, a hoisting cable associated with the boom, and pulling means associated with said support and dipper handle for shifting the dipper outwardly relative to the 95 boom under the shifting action of said boom on said support.

3. In an excavating machine, the combination of a movable boom support, a boom mounted on said support for up and down movement and for moving said support during the digging cycle, a dipper handle pivotally mounted on the outer end portion of said boom and carrying a dipper working toward the machine during digging, a hoisting cable associated with the boom, means associated with said support and moved thereby under forces exerted thereon by the boom for shifting the dipper outwardly relative to the boom, and means opposing the 105 outward shift of said dipper and for swinging it inwardly toward the boom.

4. In an excavating machine, the combination of a support pivotally mounted on the machine, a boom pivotally mounted on said support for up and down movements and for moving said support, a dipper handle pivotally mounted on the outer end portion of said boom and carrying a dipper working toward the machine during digging, a hoisting cable 125 associated with the boom, pulling means associated with said support and dipper handle for shifting the dipper outwardly relative to the boom under the shifting action of said boom on said support, and separately con- 130

trolled means opposing the outward shift of said dipper and for swinging it inwardly toward the boom.

5. In an excavating machine, the combination of a support pivotally mounted at one end on the machine, a boom pivotally mounted on said support, intermediate its ends, for up and down movements and for moving said support, a dipper handle pivotally mounted 10 on the outer end portion of said boom and carrying a dipper working toward the machine during digging, a hoisting cable associated with the boom, and a cable connection between the free end of said support and the dipper handle for shifting the dipper and 15 dipper handle outwardly relative to the boom under the shifting action of said boom on said support.

6. In an excavating machine, the combination of a boom mounted for up and down 20 movements, a dipper handle pivotally mounted on the outer end portion of said boom and carrying a dipper working toward the machine during digging, a hoisting cable for 25 raising and lowering the boom, a movable supporting means for the boom for converting the weight component of the boom acting along the same into a pulling force exerted on the dipper handle for swinging the dipper 30 per outwardly relative to the boom, and means for transmitting this pulling force to said dipper handle.

7. In an excavating machine, the combination of a boom mounted for up and down 35 movements, a dipper handle pivotally mounted on the outer end portion of said boom and carrying a dipper working toward the machine during digging, and means including a movable support for the boom operatively connected to said dipper handle and 40 actuated by a weight component of the boom for swinging the dipper handle and dipper outwardly relative to the boom, said means under the action of the boom exerting a lesser 45 swinging force upon the dipper handle when the boom is lowered into digging position than when said boom is in an elevated position.

8. In an excavating machine, the combination of a base, a swinging boom, a dipper handle pivotally mounted on the outer end portion of said boom and carrying a dipper working toward the machine during digging, movable means for supporting the inner end of the boom for movement relative 50 to said base, means for moving the dipper handle relative to the boom by said supporting means during the digging cycle, and means for raising and lowering said boom.

60 9. In an excavating machine, the combination of a base, a lever pivotally mounted on said base, a boom pivotally mounted on said lever for up and down movements and for moving said lever during the digging cycle, 65 a dipper handle pivotally mounted on the

outer end portion of said boom and carrying a dipper working toward the machine during digging, a hoisting cable associated with the boom, and means operatively connecting said lever, at a point spaced from the connection of said lever to said base, to said dipper handle for effecting shifting movements of the dipper and dipper handle relative to the boom on the movement of said lever.

In testimony whereof, I affix my signature. 75
ARTHUR ORLOFF.
